UNITED STATES PATENT OFFICE.

JAMES S. LAWRENCE, OF SAN JAVIER, MEXICO.

WATER-ELEVATING APPARATUS.

No. 915,778.

Specification of Letters Patent. Patented March 23, 1909.

Application filed August 7, 1908. Serial No. 447,407.

To all whom it may concern:

Be it known that I, JAMES S. LAWRENCE, citizen of the United States, residing at San Javier, Sonora, México, have invented certain new and useful Improvements in Water-Elevating Apparatus, of which the following is a specification.

This invention relates to water elevating apparatus particularly such as is designed for draining mines, but my improvements may be employed for elevating water from various other places.

The invention consists generally in forming the discharge duct of the usual force pumping apparatus into a siphon, and providing the discharge end of the siphon with a valve for automatically controlling the discharge end of the siphon in such manner as to prevent the entrance of air into the siphon, should the action of the pump fail to keep the siphon properly supplied with water, or should the pump cease to operate.

The invention further consists in certain novel details of construction and combinations and arrangements of parts all as will be now described and pointed out particularly in the appended claims.

In the accompanying drawings: Figure 1 is a diagrammatic sectional elevation illustrating a water elevating plant or system embodying the present invention. Fig. 2 is an elevation of the discharge end of the siphon and the preferred form of automatic valve controlling the outflow. Fig. 3 is a plan view of the valve and associated parts.

Similar letters of reference in the several figures indicate the same parts.

A shaft or mine to be drained is indicated diagrammatically at A in Fig. 1 of the drawings and the discharge point for the water is indicated at B. In order to be discharged from the mine or shaft, the water must be elevated to a higher level than the discharge point, thus as shown, the mouth of the shaft 45 A is the highest point intermediate the intake or pump and the discharge or out-flow.

Extending from the water level in the shaft up to the mouth of the shaft and down to the discharge point is a pipe or conduit C, of proper cross-sectional area to handle the desired quantity of water and at a proper intermediate point a pump D is located. This pump may, in accordance with usual practice, be located in the shaft near the intake and is adapted to force the water up 55 through the pipe or conduit, but in accord-

ance with the present invention it is relieved by the siphonic action of the upper end of the conduit, from the work of elevating the water to a greater height than is necessary for the siphon to become effective. Without some means, however, to control the out flow, the siphonic action would be ineffective or at best irregular and would, under some conditions, impose a greater load on the pump than would exist if no siphon were employed. To overcome this difficulty, I provide a valve by means of which, under all conditions, the pipe or conduit may be kept full of water down to the out-flow and at the same time a discharge aperture is provided which may be increased or diminished in size in accordance with the flow at any particular moment. This valve is preferably automatic in its action and controlled by the pressure of water in the conduit in proximity to the discharge aperture. As illustrated, the valve is a simple gate valve E, sliding in ways F formed on a head or casing G secured to or forming the discharge end of the conduit. A branch pipe or conduit H leads from the main conduit C at a point above or in front of the valve to a tank or cistern K. The branch H preferably opens into the top of the conduit C as shown in Figs. 2 and 3 and enters the tank at approximately the same level, whereby the normal low water level in the tank is determined.

A float M is located in the tank and connected by means of a lever N and link O with the valve whereby as the water level rises in the tank owing to increased pressure in the main conduit, the float will rise and open the valve and as the water level lowers by reason of the decreased pressure in the main conduit and consequent reverse flow of water through the branch, the float will drop and close the valve more or less, thus the actual discharge opening is regulated properly to maintain the conduit full of water, down to the discharge opening and the siphonic action will continue with equal force regardless of any irregular action of the pump and without danger of being interrupted by the entry of air.

The tank may be provided with a supplemental discharge as indicated, for instance, at P, where a valved outlet is illustrated adapted to be regulated by hand so as to permit a certain proportion of the water flowing into the tank to discharge, but it will be understood that any well-known

arrangement may be employed for regulating the height to which the water may rise in the tank or for operating the valve through the medium of the flow of water in 5 the discharge leg of the siphon.

I claim as my invention:

1. In a water elevating apparatus, the combination with a conduit having its discharge end formed into a siphon and its intake end extended to a point below the level of siphonic action, of a pump connected with the intake end for elevating the water to the level of siphonic action, a valve for regulating the size of the discharge aperture at the 10 out-flow and means whereby the position of the valve is controlled by the water within the discharge leg of the siphon.
2. In a water elevating apparatus, the combination with a conduit having its discharge end formed into a siphon and a pump connected with its intake end for elevating the water to the level of siphonic action, of a valve controlling the size of the discharge aperture of the siphon, a float controlling the 15 valve, a tank in which the valve is located and a branch connection between the conduit above the valve and the tank.
3. In a water elevating apparatus, the combination with a conduit having its dis-

charge end formed into a siphon and a pump connected with its intake end for elevating the water to the level of siphonic action, of a valve for regulating the size of the discharge opening of the siphon, a tank, a branch connection between the top of the conduit above the valve, a float in the tank and connections between the float and valve whereby the size of the discharge aperture is regulated in accordance with the water level in the tank.

4. In a water elevating apparatus, the combination with a conduit having its discharge end formed into a siphon and a pump connected with its intake end for elevating the water to the level of siphonic action, of a valve controlling the size of the out-flow 40 aperture of the siphon, a tank, a branch connection between the conduit above the valve and the tank, a supplemental discharge for the tank, a float in the tank and connections intermediate the float and valve whereby the 45 size of the discharge aperture is regulated in accordance with the water level in the tank.

In testimony whereof, I have hereunto subscribed my name.

JAMES S. LAWRENCE.
